UNITED STATES PATENT OFFICE.

PAUL H. BARZ, OF CHICAGO, ILLINOIS.

POLISHING-MACHINE.

No. 867,633.

Specification of Letters Patent.

Patented Oct. 8, 1907.

Application filed January 26, 1907. Serial No. 354,224.

To all whom it may concern:

Be it known that I, PAUL H. BARZ, a citizen of the United States, residing at Chicago, in the county of Cook and State of Illinois, have invented certain new and useful Improvements in Polishing-Machines, of which the following is a specification.

This invention is a polishing machine, particularly adapted for polishing wood surfaces, and provided with means for adjusting the angle and also the inclination of the rubbing block and for adjusting the height and the angle of the bed or work with respect to the rubbing block or blocks. Improved means are also provided for reciprocating the polishing blocks and for adjusting the same to various positions with respect to the work.

15 The machine is illustrated in the accompanying drawings, in which

Figure 1 is a side elevation thereof. Fig. 2 is a plan. Fig. 3 is a plan of a platform on which the bed which holds the work is mounted. Fig. 4 is a plan of a lower 20 platform, below the platform shown in Fig. 3. Fig. 5 is a plan view of one of the rubbing blocks. Fig. 6 is a section thereof on the line 6—6 of Fig. 5. Fig. 7 is an end elevation thereof. Figs. 8 and 9 are details in section of a sliding collar, which is connected to the rubbing blocks and allows angular variation thereof to accommodate irregular surfaces. Fig. 10 is a detail in section of a sprocket nut for shifting the supporting frame of the rubbing blocks.

Referring specifically to the drawings, A indicates 30 the frame of the machine, of substantially rectangular shape or construction suitable to support the parts hereinafter mentioned.

B is a movable or adjustable polishing frame which supports the polishing blocks indicated as a whole at b. 35 The frame B is provided with a lower grooved bar B' which has grooves in its sides forming guides for the blocks b. Said blocks slide back and forth on said guide bar, and one of the blocks is provided at the end with a head E' (see Figs. 8 and 9) which fits over or 40 around the guide bar B' and is tongued and grooved to correspond therewith and is arranged to slide thereon. The head E' has a circumferential rib e which fits in a corresponding groove in a collar E. This collar is connected by pivoted links D² to a cross rod d² extending 45 between blocks D slidably mounted upon the top bars of the frame. Said blocks also have a cross bar d' connected by rod D' to an adjustable crank block D⁴. This block is mounted in a frame consisting of rods f, cross pieces f' and f² at the end, and a screw F which extends 50 through the block D⁴. The cross piece f² is fixed to the end of the drive shaft D³, the whole forming an adjustable crank. By operating the screw F the position of the block D⁴, and consequently the throw of the crank, may be varied.

55 The guide bar B' may be turned on its longitudinal

axis by means of the hand wheel B² to accommodate the polishing blocks to inclined or irregular work and the grooved collar and block E and E' allows this to be done, since the latter will turn within the former to any desired extent. One or more polishing blocks can be 60 used, and when more than one are used they are connected by means of links b', as shown in Figs. 1 and 2.

K is the upper platform or bed upon which the block or object to be polished rests, said block being indicated at b³. This platform is held in position by 65 means of a pin or pivot L' which projects upwardly from the platform L into a socket L² in the bed K. Said bed rests at its outer or end edges upon rollers l' which are carried in frames formed by pairs of parallel bars l, and these bars are supported at opposite 70 ends upon links l² which are pivoted at one end to the bars and at the other end to ears m on the platform L. The bars l are connected by a cross bar l³, against which bears a roller o' carried at the end of the lever o. When the lever is straightened, as indicated in 75 dotted lines in Fig. 3, the effect is to shift the frames l so that they are lifted, in consequence of the swing of the links l², thereby lifting the bed K. The lever o stops and locks against a pin p. The platform L is also provided with rollers n, upon the top thereof. 80 By swinging the lever o to the angular position, as shown in full lines in Fig. 3, the frame carrying the rollers l' will be dropped, allowing the bed to lower until it rests upon the rollers n. When said bed K is lowered upon said rollers it can be rotated freely 85 upon its pivot pin L', thus providing means to place the surface being polished at any desired angle. Hence to turn the object being polished to any desired angle it is simply necessary to drop the bed upon the rollers n and turn the same, after which the lever o is straightened to lift the rollers l' and raise the bed and bring the work in contact with the polishing blocks. To further vertically adjust the bed K there is provided, under the platform L, a lower platform M, at the corners of which are vertical screws r having sprockets q 90 secured thereto, with a chain s extending around the sprockets. One of the screws has a hand wheel t, as shown in Fig. 1, by turning which all the screws may be turned, and the platform L and bed K lifted accordingly. This is to accommodate articles of any 100 thickness which may be placed upon the bed K. Furthermore, means are provided to reciprocate or move the bed and platforms as a whole, under the rubbing blocks. Thus the lower platform M has depending brackets O which carry rollers N which travel in guides 105 P in the end frames of the machine. Said platform moves crosswise, at right angle to the movement of the polishing blocks b, and thus a double movement is attained upon the surface being polished. The reciprocation of the platform M is effected by means of 110

a connecting rod J which is attached at one end to the platform and at the other end to a crank wheel I which is rotated by means of beveled gears H and H' driven from the driving shaft D³ by means of a belt G' and 5 appropriate pulleys. The crank wheel I is preferably made adjustable to vary the throw.

The polishing block b is so constructed that its rubbing surface can be turned at an angle to the line of reciprocation, as illustrated in dotted lines in Fig. 2. 10 This enables the blocks to be used lengthwise or crosswise, or at any other angle desired, to accommodate the work being polished. Thus, referring to Figs. 5, 6 and 7, each block consists of an upper part 1 with a recess in the side to receive a clamping block 5 and a 15 circular recess at the center to receive a pivot piece 4 which is undercut, as shown. The lower part 3 of the block may thus be turned crosswise or at an angle on the part 4 as a pivot, with respect to the upper part 1, which latter has grooves 2 to travel on the ribs of 20 the guide bar B'. At the ends of the block are projections 9 with ribs 9', said projections being fastened to the block with screws 10. A cross piece 6, with grooves cut in the ends thereof, to slide on the ribs 9' is provided at each end of the block and is moved by 25 means of set screw 7 which passes through said cross piece and through the ends of the piece of felt or polishing material 8, and into the ends of the block. The upper and lower parts of the block are held together by the screw 4', and when the lower part of the block 30 is turned to the desired angle it may be locked by the screw 11.

The frame B and the blocks carried thereby are adapted to be shifted back and forth across the width of the machine by means of sprockets C connected 35 by a chain belt C³, which turns said sprockets around the screws c, which extend horizontally across the opposite ends of the machine. Said screws may be operated by hand or in any other suitable way. The frame B may also be raised and lowered by means of 40 the lever C² projecting from one of the links C' by means of which the frame is supported upon the screws, and when so raised or lowered can be held in any desired position by the set screw C⁴ binding on the screw c.

The various adjustments provided accommodate 45 the machine to a large variety of work and the compound motion effected through the lateral reciprocation of the rubbing blocks gives a very efficient action and prevents uneven work. It will also be seen that the bed is capable of vertical and angular adjustment 50 and that the frame carrying the rubbing blocks is capable of vertical and lateral adjustment. Consequently all parts of the work may be readily reached and rubbed in various directions.

I claim:

55 1. In a polishing machine, the combination with a bed for the work, of a vertically and laterally adjustable frame above the same, having a guide bar, a rubbing block slideable on the guide bar, and driving devices connected to the block, including a sliding cross bar and a link connecting

the bar and block and movable along the bar according to 60 the lateral movement of the said frame.

2. In a polishing machine, the combination with a main frame, and a bed for the work supported thereon, of a guide bar adjustable laterally above the bed, a polishing block slideable on the guide bar, a pair of spaced blocks 65 slideable on the top of the frame and having a cross bar connecting the same, a link pivotally connected to the polishing block and to the cross bar, and means to reciprocate said sliding blocks.

3. In a polishing machine, the combination with a main 70 frame and a bed for the work, of a frame suspended within the main frame and having a guide bar which may be turned on its longitudinal axis, a polishing block mounted upon the guide bar and having a circular head extending around the guide bar, a collar rotatably mounted on the 75 head, and means connected to the collar to reciprocate the block.

4. In a polishing machine, the combination with a main frame and a bed for the work, of a polishing block 80 slideable over the work, a pair of blocks slideable on the upper part of the frame and having a connecting rod, a link pivotally connected to the rod and to the block and adjustable laterally along the rod, and means to reciprocate the said sliding blocks.

5. In a polishing machine, the combination with a main 85 frame, of a bed for the work, having vertical and angular adjustment therein, a frame mounted in the main frame above the bed and having vertical and lateral adjustment, rubbing blocks carried by the frame, and means to reciprocate the blocks.

6. In a polishing machine, the combination with a bed, and means to reciprocate the same, of a polishing block, and means to reciprocate the same above the bed, at an angle to the line of reciprocation of the bed.

7. In a polishing machine, the combination with a bed 95 pivoted at the center, of a platform under the bed having rollers thereon, the bed being rotatable upon said rollers, and means to lift the bed above said rollers and to lower the same thereon.

8. In a polishing machine, the combination with a vertically adjustable platform having rollers upon the top thereof, of a bed pivoted upon the platform and rotatable upon the rollers, the bed being also vertically movable, and means to raise and lower the bed with respect to said 100 rollers.

9. In a polishing machine, the combination with a platform, of a frame above the same, pivoted links between the frame and the platform, means to swing the links to raise or lower the frame, a bed mounted upon the frame and movable up and down therewith, the frame having rollers 110 on which the bed rests and means to reciprocate the bed.

10. In a polishing machine, the combination with a guide bar, of a rubbing block slideable thereon, said block being formed of upper and lower parts pivoted together, the former of which engages the bar and the latter of 115 which may be turned on the pivot at various angles with respect to the former.

11. In a polishing machine, the combination with a main frame and a bed for the work, of a frame mounted within the main frame above the bed and having a lower guide 120 bar which may be turned on its longitudinal axis, means to raise and lower the latter frame, means to shift the same laterally, a polishing block mounted on the guide bar and capable of being turned therewith to various angles, and means to reciprocate the block on the bar.

In testimony whereof I affix my signature, in presence of two witnesses.
